CLAIM

The ornamental design for a vehicle seat, as shown and described.

DESCRIPTION

FIG. 1 is a front perspective view of a vehicle seat showing our new design in a state that one table is extended;

FIG. 2 is a rear perspective view thereof in a state that one table is extended;

FIG. 3 is a front view thereof;

FIG. 4 is a rear view thereof;

FIG. 5 is a right side view thereof;

FIG. 6 is a left side view thereof;

FIG. 7 is a top plan view thereof; and,

FIG. 8 is a bottom view thereof.

The broken lines are shown for illustrative purposes only and form no part of the claimed design.
